DESIGN FOR A STOCKING TUBE

David Lewis, New York, N. Y.

Application August 6, 1938, Serial No. 79,148

Term of patent 3½ years

To all whom it may concern:

Be it known that I, David Lewis, a citizen of the United States of America, residing in the city of New York, county of New York, and State of New York, have invented a new, original, and ornamental Design for a Stocking Tube, of which the following is a specification, reference being had to the accompanying drawing, forming part thereof.

Fig. 1 is a front view of a stocking tube, showing my new design.

Fig. 2 is a perspective view thereof particularly showing the transparent portion.

Fig. 3 is a perspective view of the stocking tube.

I claim:

The ornamental design for a stocking tube, substantially as shown.

DAVID LEWIS.
